TYING MACHINE

Benjamin H. Bunn, Chicago, Ill., assignor to
B. H. Bunn Company, Chicago, Ill., a corpora-
tion of Illinois

Application February 10, 1942, Serial No. 430,254

8 Claims.

(Cl. 100—31)

My present invention relates to package tying machines and contemplates more specifically the wrapping with twine and tying of roll-like packages, which may be meat products, with or without a wrapping of paper or other sheet-like material.

In the past I have developed a number of package tying machines, for example, that disclosed in my Patent No. 1,606,290, issued November 9, 1926. Since a number of the features of the present invention are similar to those of the construction of that patent, it will be assumed, in order to simplify the present specification, that the reader is familiar with the construction and operation of the machine described in the above-mentioned patent.

Attempts to use machines such as those described in my above-mentioned patent for the tying of roll-like packages, such as rolled veal roasts, and other meat products, have not been fully satisfactory due to the fact that such meat products usually have an external layer of fat which has a tendency to rub off and adhere to the package supporting tables, accumulating on the tables, and thus interfering with the manipulation of the products being tied.

An object of the present invention is to avoid this objection. To this end I heat the package supporting surfaces so as to melt a portion of the fat contained in such products for the purpose of self-lubrication, and to maintain the package support at a controlled temperature for such purpose.

On completion of the twine wrapping, the terminal reaches of the wrapped twine are brought together for engagement by the knotting beak of the tying mechanism, as in my above-mentioned patent. A stop is customarily provided on the table, to be engaged by a bottom edge of an ordinary rectangular package, whereby to position the edge of the package in definite relation to the knotting mechanism. However, where the package lacks a definite bottom edge to engage the package stop, as is the case with a package of generally circular cross-section, the two terminal reaches of the twine wraps sometimes are not positioned to extend at direct angles from the twine-engaging portion of the "draw slide" which draws the twine into knotter-engaging position. The result is that one or the other of such reaches of twine is not properly engaged by the knotter beak for performance of the knotting.

A further object of my invention is to make a tying machine with the draw slide or twine slide arranged definitely to maintain the terminal

reaches of the twine wraps employed in wrapping a package at correct angles, as well as at correct position, for engagement by the knotter beak, even when tying packages of circular or irregular cross section.

Unlike a tying machine for rectangular packages where the location of the knotter is but slightly displaced from the stop on the table which engages the edge of the package, for roll-like packages of generally round or oval cross-section, the knotter is best located directly below the line of tangential contact with the table. This line of supporting contact will come substantially below the center of gravity of the package, whereas in a wide rectangular package the center of gravity is displaced a considerable distance to the side, and this tends to create an off-center torque stress upon the table—especially the floating or suspended island table.

By my invention, I am able to employ rather narrow package supporting tables where the machine is especially designed for the wrapping of such roll-like packages. Also, since all such packages normally will be positioned to rest on the same narrow supporting area over the knotter, the centers of various sized packages will be located in substantially the same vertical plane above this narrow supporting area. I prefer, therefore, to locate the twine arm with its axis of rotation substantially directly over the knotter, since this arrangement provides for an approximately equal swing of the twine arm on both sides of this plane during the rotation of the twine arm, and thus permits the use of a twine arm of minimum radial throw for a predetermined maximum diameter of package to be wrapped.

Since the table is narrow, it does not have to be supported against strong off-center torque stresses. This is due to the fact that packages supported on the table for wrapping will be positioned almost directly below the pivotal support of an island table, such as is described in my above-mentioned patent.

Another object of my invention is to improve and simplify the anchoring means for holding the island table against pivotal movement during a wrapping operation, despite the necessity of the twine passing through the anchoring means.

A further object in connection with the anchoring means is to employ the movement of the reach of twine as it passes around a package during a wrapping operation, to operate a twine trap without releasing the island table from anchored condition.

These and other objects and advantages of the invention will be more fully set forth in the following description and the accompanying drawings.

In the drawings, of which there are four sheets:

Fig. 1 is a view in side elevation of a tying machine embodying my present invention, a roll-like package being indicated in position thereon in dotted lines;

Fig. 2 is an enlarged fragmentary section on the offset planes of the broken line 2—2 of Fig. 1;

Fig. 3 is an enlarged fragmentary section on the offset planes of the broken line 3—3 of Fig. 1;

Fig. 4 is an enlarged fragmentary section on the plane of the line 4—4 of Fig. 1;

Fig. 5 is an enlarged detail perspective view showing parts of a twine trap as they would appear in operating position, a twine catcher and a reach of twine being shown in position to operate the twine trap;

Fig. 6 is a schematic diagram of an electrical circuit employed in a heating arrangement for the package supporting surfaces of the machine; and

Fig. 7 is an enlarged detail perspective view of a draw slide with double twine-engaging portions to hold the end reaches of a wrap of twine in proper position for engagement by a knoter beak.

Referring to the drawings in detail, a frame 11 comprises end frame members 12 and 13 connected by front and rear members 14 and 15. The frame is supported on swiveled casters 16. A drive motor 17 is mounted upon a supporting plate 18 carried by the frame which also supports a twine bucket 19.

The drive motor has driving connection through a V-belt 20 with a clutch pulley 23 which is mounted to rotate freely on a clutch shaft 24 when a clutch 25 is held in released position; and to have driving engagement with the clutch shaft 24 when the clutch is in engaged position.

The clutch operating mechanism generally is similar to that of my above referred to patent, and comprises a clutch plate 26 adapted to engage the side face of the clutch pulley 23 when the clutch is in engaged position. The clutch plate has a throw-out collar 27 which is engaged by the forked lower end of a clutch operating lever 28, pivoted on a support member 29 carried by the frame 11 (see Fig. 2).

A coil spring 30 normally holds the clutch in engaged position, the clutch being moved to released position by a cam 33, mounted on the side of the main cam block 34. The cam 33 is adapted to engage a slip link 35, which normally is positioned between the cam 33 and a roller 36 carried on the top of the clutch operating lever 28. The cam 33, at the completion of each complete revolution of the cam block, engages the slip link 35, forcing it laterally against the roller 36. This moves the clutch lever 28 pivotally, causing the forked lower end of the clutch lever to move the clutch to released position.

A foot pedal 37 is connected to a rod 38 which in turn has pivotal connection with one arm of a bell crank lever 39, pivoted on the frame 11, and having the other end thereof pivoted to the slip link 35. A coil spring 40 is held in tension between an arm of the bell crank lever and a pin 43 mounted on the frame, normally to hold the bell crank lever in the position illustrated in Fig. 2. This action of the bell crank lever under the tension of the coil spring moves the slip link into position between the roller 36 on the upper end of the clutch lever and the side cam 33, to move the clutch operating lever to its clutch-releasing posi-

tion. Depressing the foot pedal moves the bell crank lever 39 pivotally in a counterclockwise direction from the position illustrated in Fig. 2, thereby withdrawing the slip link and releasing the clutch lever. This release of the clutch lever permits the coil spring 30 to move the clutch to engaged position. Upon releasing the foot pedal the clutch lever 28 will be returned to clutch-releasing position through the action of the cam 33 on the slip link 35 upon the completion of one revolution of the cam block 34.

A pinion 44 is keyed to the clutch shaft 24 and has toothed driving connection with a mutilated gear 45, keyed to the same shaft as the cam block 34. The right-hand half of the mutilated gear, as illustrated in Fig. 1, is fully toothed throughout its entire periphery, while the left-hand half of the mutilated gear has the teeth removed therefrom, with the exception of a number of teeth sufficient to cause one complete rotation of a twine arm drive gear 46 upon each complete rotation of the mutilated gear 45.

The twine arm drive gear 46 has a chain drive sprocket 47 secured coaxially therewith, and a drive chain 48 is passed around the drive sprocket 47 and a driven sprocket 49, which is keyed to the hub of a twine arm support 53. The twine arm support has a hollow hub portion 50 through which the twine 54 is adapted to be passed, the hub having a lateral opening 55 adjacent a twine arm supporting portion 56. A crank-like twine arm 57 is mounted in the twine arm supporting portion 56.

A twine guide 58 is provided on the twine arm, the outer end of the twine arm having an axially extending opening 59 therein, with a lateral opening 60 through which the twine may be threaded. The end of the twine arm is positioned to rotate in the same vertical fore-and-aft plane as that of a twine catcher 63, which is adapted to seize and retain a reach of twine during a wrapping operation, as brought out in my above-mentioned Patent No. 1,606,290.

An island table 61 is mounted on a support member 64, which is journaled on the outer end of the twine arm hub coaxially therewith. An island table support plate 65 is secured to the inner or right-hand face of the journaled support member, as it appears in Fig. 1. The plate 65 is bent at right angles, as at 66, at the desired level of the island table top, and extends horizontally to a point near the plane of the twine wrap.

An island table top member 67 of sheet metal is secured to the top of the horizontal portion of the bent plate 65, and a pair of support rods 68, which preferably are rectangular in cross-section, are bent to the shape illustrated in Fig. 1, and are secured in position to support and reinforce the island table top.

A star-wheel supporting bracket 69 is connected to the underside of the island table to extend downwardly therefrom, the lower end of the bracket terminating in a point 70 and extending well below the lowermost portion of a star wheel 73, which is pivoted on a pin 74 carried by the bracket to rotate in a plane at right angles to the plane of the twine wrap. The downwardly extending point 70 guides the twine as it engages the star wheel and prevents the twine from being swung to the rear of the star wheel which would prevent proper completion of the twine wrap.

A light coil spring 75 may be mounted to encircle an extending portion of the pivot pin 74, and is held in compression between the bracket 69 and a washer 76 carried by the extending por-

tion of the pivot pin, to exert a resilient axial force on the pivot pin which holds it in frictional engagement with the bracket, and thus prevents any tendency toward a free spinning movement of the star wheel. This arrangement insures that the star wheel will be in proper position to receive each successive reach of the twine as it is carried around by the twine arm.

A slotted bracket 77 is mounted with the slot thereof vertical, and adapted to receive the points of the star wheel as it rotates. The bracket is mounted on the frame and projects toward the star wheel a distance which brings its vertical face slightly beyond the plane of the twine wrap so that the twine will be cammed over the slanting lower end of the bracket, and will move slidably upwardly along the face of the bracket as the twine is swung upwardly from the position illustrated in Fig. 2 during a wrapping operation. The bracket is positioned so that the vertical slotted portion thereof will extend to less than the full depth of the points of the star wheel to avoid any shearing action on the twine between the star wheel and the slotted guide.

The angles between successive teeth or points of the star are such that each succeeding point will enter the slotted guide-way before the preceding point leaves it, so that at least one point of the star always is in position within the slotted guideway. This anchors the island table to the frame against pivotal movement.

A fixed table 18 is supported on the frame 11, and extends outwardly beyond the frame, being supported by brackets 79, the lower ends of which are secured to the end frame 13.

An outlet box 80 is secured to the underside of the fixed table, and within this outlet box, as illustrated in Fig. 4, a contact heater 81 is applied to the underside of the table. A second contact heater 82 may be applied to the underside of the fixed table exteriorly of the outlet box. These contact heaters are mounted directly beneath the desired longitudinal centerline of a roll-like package 83, indicated in dotted lines in Figs. 1 and 2. The position of the package on the table is determined by a raised abutment 84 which preferably is formed up from the material of the table top itself along one side of the desired support area, and is adapted to engage a curved lower side portion of the package to bring it to the desired position.

A thermostatic switch 84 is mounted within the outlet box, one contact member 91 of the switch being connected to a conductor 85 which is connected through a manually controlled switch 86 to one conductor 87 of a suitable electric power line. The other contact member 88 of the thermostatic switch is connected by a conductor 89 to one side of the heater 81. A branch conductor 90 is connected from the conductor 88 to one side of the second heater 82.

A conductor 93 of the electric power line is connected to the second terminal of the heater 81, while a branch conductor 92 from this line is connected to the second terminal of the heater 82.

Thus, assuming that the line conductors 87 and 93 are connected to a suitable source of electrical energy, when the thermostatic switch contacts 88 and 91 are closed the circuit to the heaters 81 and 82 will be completed.

The circuit to the heater 81 will be from the line conductor 87, through switch 86, the closed switch elements 88 and 91, the conductor 89, the heater 81 and thence to conductor 93, constitut-

ing the opposite side of the line. The second heater 82 is connected in parallel with the first by the conductors 90 and 92.

In order to heat the island table 61 without the necessity of complicated and costly wiring, which would be necessary to carry electrical current to a contact heater of the type illustrated at 81 and 82 through the pivotal mounting of the island table, I employ a radiant heater 94 mounted below the island table, and positioned to direct radiant heat rays against the under surface of the table.

The radiant heater comprises a pair of strap-like mounting brackets 95 and 96 supported on the front frame member 14, and carrying a box-like sheet metal support member 96. A tubular housing 97, of asbestos or other suitable heat insulating material, has an elongated opening 98 in its top, and a pair of radiant heating elements 99 and 100 are mounted within this housing. A covering of wire screen is mounted over the opening 98 to prevent undesired foreign particles from falling into the heater. The radiant heater elements 99 and 100 preferably have one terminal of each connected together as by a conductor 105, and are connected, by conductors 103 and 104, to the conductors 89 and 93 respectively. The heating units in this radiant heater thus are connected in parallel with the contact heaters 81 and 82, so that all of the heaters are controlled by the same thermostat 84.

A draw slide 106, illustrated in Figs. 2 and 3, and in detail in Fig. 7, is mounted in the frame 11 to be slidable substantially parallel to the plane of rotation of a wrap of twine during a wrapping operation.

Synchronization of the slidable movement of the draw slide 106 with the remainder of the wrapping and tying mechanism, is accomplished by a bell-crank lever 107 which is pivoted on the frame, and has a roller 108 at the outer end of a laterally extending arm 109 thereof, the other or vertical arm 110 terminating in a bead-like head portion 113 which is mounted in a notch 114 in a projection 115 on the underside of the twine slide.

The roller 108 is held in rolling contact with a peripheral cam face 116 on the cam block 34 by a coil spring 117 connected from a pin 118 on the twine slide to the frame 11, and urging the twine slide to its normal or extreme leftward position (see Fig. 7). The cam is shaped to operate the bell-crank lever 107 to move the draw slide from its extreme leftward position toward the right to the position illustrated in solid lines in Fig. 7 after the final wrap of twine has been carried around the package being wrapped, and has been gripped by the twine catcher. This movement to the right of the draw slide carries the two strands of twine 119 and 120 to a position to the right of the knoter beak.

The draw slide is provided with two elongated slotted openings 123 and 124 mounted to receive studs 125 and 126, respectively, carried by the frame, the studs serving to guide the longitudinal reciprocal movement of the draw slide. It will be noted that the slot 123 is straight throughout its entire length, while the slot 124 has an offset portion 127 at its extreme right end as shown in Fig. 7.

The function and operation of this offset end portion of the slot is not new, but is described in detail in my Patent No. 2,182,959, issued December 12, 1939. It will be described briefly herein however, in order to avoid the necessity

of referring to that patent for its understanding. The draw slide 106 is generally hook shaped, and the short, twine-engaging portion 128 of the hook is mounted to lie directly over the twine catcher 63 when the studs 125 and 126 are in the straight portions of the slotted openings 123 and 124. In this position of the draw slide, the twine catcher could not engage a reach of twine as it was swung around by the rotation of the twine arm, since the slide, overlying the twine catcher, acts as a cam to move the reach of twine laterally beyond the twine catcher.

Therefore, during the portion of the cycle wherein the twine is to be engaged by the twine catcher, the roller 108 is on a low point of the peripheral cam face 116, which permits the spring 117 to pull the draw slide 106 to its extreme leftward position from that illustrated in Fig. 7. With the draw slide in its extreme leftward position, the studs 125 and 126 will lie at the extreme right-hand ends of their respective slots, which tends to pivot the slide clockwise about the stud 125. This action swings the left-hand end of the slide to the right sufficiently to uncover the twine catcher 63 so that it will be engaged by the reach of twine as it is swung down by the twine arm during a wrapping operation.

The right-hand end of the short, or twine-engaging portion 128 of the hook-shaped draw slide is divided horizontally into two parts 129 and 130 which comprise superposed twine engaging and positioning elements. The twine engaging elements 129 and 130 are separated from each other vertically sufficiently to receive a knotter beak 133 therebetween, and to permit the knotter beak to rotate in a counterclockwise direction therebetween as illustrated in Fig. 7, to wrap the two strands of twine 119 and 120 about itself as it performs the knotting operation.

This double twine engaging draw slide is especially useful in tying packages of roll-type, or of generally circular section. It also has solved a problem which for years has caused occasional mis-functions in the tying of other or rectangular types of packages. For instance, in cases where a package being tied was misplaced from its proper position so that one or the other of said reaches of twine might be disposed at an angle which brought it beyond the compass of the knotter beak in its rotation.

The present double-draw slide positively positions both terminal reaches of twine at a correct angle, and in a proper position to be engaged by the knotter beak regardless of any tendency they otherwise might have to assume angles less than that required for such proper engagement.

While I have illustrated a preferred embodiment of my invention, many modifications may be made without departing from the spirit of the invention and I do not wish to be limited to the precise details of construction set forth, but desire to avail myself of all changes within the scope of the appended claims.

I claim:

1. A machine for wrapping with twine and tying roll-like packages, said machine comprising a frame, a crank-like twine arm pivoted in the frame, an island table suspended beneath the pivotal axis of the twine arm, said table being elongated in the direction of the twine arm axis, a fixed table mounted laterally adjacent to and spaced from the island table, an abutment on the fixed table laterally adjacent to a vertical plane through the twine arm axis to position a

roll-like package having its side contacting the abutment and with its central axis substantially parallel to and in vertical alignment with the twine arm axis, and a knotter mounted substantially directly below the twine arm axis, to accommodate a package of maximum size and weight, with a minimum torque on the island table, for a predetermined throw of the twine arm.

10. 2. A machine for wrapping with twine and tying roll-like packages, said machine comprising a frame, a crank-like twine arm pivoted in the frame, an island table suspended beneath the pivotal axis of the twine arm, said table being elongated in the direction of the twine arm axis, a fixed table mounted laterally adjacent to and spaced from the island table, a laterally sloping abutment having a face thereof disposed at an acute angle to the fixed table top to position a roll-like package, supported on the fixed table and in contact with the abutment, with the axis of the package in substantial vertical alignment with the axis of the twine arm, and a knotter mounted substantially directly below the twine arm axis, to accommodate a roll-like package of maximum size and weight, with a minimum torque on the island table, for a predetermined throw of the twine arm.

3. In a machine for wrapping roll-like packages, said machine comprising a frame, a crank-like twine arm pivoted thereon, and a narrow island table pivotally suspended from the twine arm; a star wheel twine trap member pivoted below the island table to rotate in a vertical

35 plane parallel to the pivotal axis of the twine arm, a slotted member mounted to receive successive points of the star wheel, the angular distance between the star points being less than that portion of the star wheel subtended by the slotted member, to cause each successive star point to enter the slotted member before the preceding one is released, thereby to anchor the island table against pivotal movement, the slotted member being positioned to pass a reach twine over the

40 face thereof against a point of the star wheel during a wrapping rotation of the twine arm pivotally to move the star wheel and pass the reach of twine therethrough.

4. In a machine for wrapping roll-like packages, said machine comprising a frame, a crank-like twine arm pivoted thereon, and a narrow island table pivotally suspended from the twine arm; a wheel pivoted below the island table to rotate in a vertical plane perpendicular to that

55 described by the end of the twine arm during a rotation thereof, a plurality of radially projecting arms on said wheel, a guide member mounted on the frame and having anchoring engagement with at least one of the arms on said wheel, the guide member being mounted in the path of the twine during a wrapping operation to guide the twine against an arm of said wheel to move said arm past the guide member to carry the twine beyond the guide member, the arms being angularly spaced apart to bring each successive arm thereof into anchoring engagement with the guide member before the preceding one leaves it.

5. In a machine for wrapping roll-like packages, said machine comprising a frame, a crank-like twine arm pivoted thereon, and a narrow island table pivotally suspended from the twine arm; a twine trap comprising a bracket secured to the underside of the island table to extend downwardly therefrom, a star wheel pivoted on the bracket to rotate in a plane intersecting the

plane of rotation of a wrap of twine during a wrapping operation, an anchoring member mounted on the frame and having intersecting anchoring engagement with at least one point of the star wheel, the star wheel and the anchoring member being mounted with their line of intersection substantially in the path of rotation of a reach of twine as it is carried around a package, whereby the twine engages the point of the star in anchoring engagement with the anchoring member, thereby rotatively moving the star wheel to move said point out of engagement with the anchoring member, and to move the next succeeding point into engagement with the anchoring member, the twine passing through the twine trap thus formed while maintaining the anchoring engagement of the island table.

6. In a machine for wrapping roll-like packages, said machine comprising a frame, a crank-like twine arm pivoted thereon, and a narrow island table pivotally suspended from the twine arm; a twine trap comprising a bracket secured to the under side of the island table, the lower end of the bracket terminating in a point, a star wheel pivoted on the bracket to rotate in a plane intersecting the plane described by the rotation of a wrap of twine during a wrapping operation, a cam face extending from the point on the lower end of the bracket toward the plane of the twine wrap to cam a reach of twine toward said plane of the twine wrap, an anchoring member mounted on the frame and having anchoring engagement with at least one point of the star wheel, the star wheel and the anchoring member being mounted with their line of intersection substantially in the path of rotation of a reach of twine as it is carried around a package, whereby the twine engages the point of the star in anchoring engagement with the anchoring member, thereby rotatively moving the star wheel to move said point out of engagement with the anchoring member, and to move the next succeeding point into engagement with the anchoring mem-

ber, the twine passing through the twine trap thus formed while maintaining the anchoring engagement of the island table.

7. In a package tying machine having a frame, a package support mounted thereon, means for carrying a reach of twine around a package on the package support, a twine catcher mounted to catch and hold an initial and a terminal reach of a wrap of twine, and a knotter mounted on the frame and offset horizontally from the twine catcher; a cyclically operated draw slide having a pair of vertically offset twine engaging portions mounted beyond the twine catcher from the knotter, and adapted to move toward the knotter at a predetermined point in a wrapping cycle to carry a reach of twine toward and beyond the knotter beak, the twine engaging portions of the draw slide being separated vertically from each other to receive the knotter beak therebetween.

8. In a package tying machine having a frame, a package support mounted thereon, means for carrying a reach of twine around a package on the package support, a twine catcher mounted to catch and hold an initial and a terminal reach of a wrap of twine, and a knotter mounted on the frame and offset horizontally from the twine catcher; a cam-controlled draw slide mounted for horizontal reciprocating motion on the frame, a first twine engaging draw slide element normally positioned beyond the twine catcher and adapted to move toward and beneath the knotter beak to carry a reach of twine extending upwardly from the twine catcher toward and beyond the knotter and a second twine engaging draw slide element spaced upwardly from the first twine engaging element and adapted to move toward and above the knotter beak simultaneously with the first to hold a reach of twine between the first and second twine engaging elements in proper position for seizure by the knotter.

BENJAMIN H. BUNN.
